UNITED STATES PATENT OFFICE.

GEORGE E. DOWNE, OF CHICAGO, ILLINOIS, ASSIGNOR TO THE AMERICAN RADIATOR COMPANY, OF NEW JERSEY.

DESIGN FOR A HEATER.

SPECIFICATION forming part of Design No. 33,203, dated September 11, 1900.

Application filed August 13, 1900. Serial No. 26,792. Term of patent 14 years.

To all whom it may concern:

Be it known that I, GEORGE E. DOWNE, a citizen of the United States of America, residing at Chicago, county of Cook, and State of Illinois, have invented and produced a new and original Design for Heaters, of which the following is a specification, reference being had to the accompanying drawing, forming a part thereof and showing the heater in elevation.

As shown in the drawing, the leading or material feature of my design consists in the columnar form of the heater, the column consisting of a base-section A in the form of a truncated cone, a slightly-tapering shaft-section B, rising from the base-section, a super-shaft-section C, rising from the section B and being cylindrical in form, and a capital D, being of greater diameter than the super-shaft and terminating above in the form of a flattened dome.

The wall of the base A has an oblong rectangular aperture bounded by an approximately oblong rectangular frame E. The wall of the shaft B has an oblong rectangular aperture bounded by an oblong rectangular frame F. Intermediate of the sections B and C there is a narrow band G. Encircling the upper portion of the supershaft C there is a band H.

30

I claim as my invention—

The design for a heater, as herein shown and described.

In testimony whereof I have signed my name to this specification in the presence of 35 two subscribing witnesses.

GEORGE E. DOWNE.
